COMPRESSOR UNLOADING MECHANISM

Paul A. Condit, Mount Vernon, Ohio

Application October 3, 1939, Serial No. 297,663

5 Claims. (Cl. 230—21)

The invention relates to compressor unloading mechanisms of the clearance chamber type such as are used to regulate the output of the compressor in accordance with operating requirements, and aims primarily to provide such a mechanism by which straight line regulation may be secured, i. e. increase or decrease in the unloading effect which is substantially proportional to requirements, as contrasted to step by step unloading. Heretofore it has been possible by speed control of the prime mover which drives the compressor, to obtain substantially straight line regulation of the compressor output from maximum down to minimum speed of the prime mover, but for unloading down to an output lower than afforded by such minimum speed, it has been necessary in actual practice to resort to supplementary unloading devices which operated in step by step fashion, with the result that straight line unloading was not achieved in this part of the range. To eliminate the above objections it has been proposed to use clearance pockets of variable volume, involving the use of a piston having a screw adjustment to alter the volume of the clearance chamber, but these proposals have not proved out to be practical on account of the high pressures involved.

The present invention accordingly aims to provide a compressor unloading mechanism wherein the volume of the clearance pocket may be accurately regulated in a practical and satisfactory manner to conform to operating requirements, and avoiding the objections heretofore met with in practical use. In accordance with the present invention, in its broader aspects, the volume of the clearance chamber is regulated by introducing into or withdrawing from the chamber as needed, a suitable fluid medium under pressure, preferably liquid such as lubricating oil, the quantity of liquid which is in the clearance chamber at any particular time determining the effective volume of the chamber from the standpoint of the extra clearance which it adds to the cylinder space of the compressor, and therefore the extent of its unloading effect upon the output of the compressor. The amount of liquid present in the clearance chamber is regulated to conform to operating requirements, and by combining a variable clearance chamber of the above character with speed control, as above mentioned, straight line unloading may be obtained in a practical manner down to 80%, or more. The range of straight line unloading may be further increased by combining such a variable clearance chamber with other supplementary unloading devices. The above and other objects and advan-

10 tages of the invention will be in part obvious and in part specifically referred to in the specification hereinafter contained which, taken in conjunction with the accompanying drawings, discloses certain preferred forms of unloading mechanism which may be used in carrying out the invention. From the standpoint of the invention in its broader aspects, however, such disclosure should be considered as merely illustrative of the principles of the invention. In the drawings—

15 Fig. 1 is a longitudinal sectional view largely schematic showing the head end of a compressor cylinder having associated therewith a clearance chamber constructed to operate in accordance with the invention, and showing diagrammatically controlling devices suitable for regulating the effective clearance volume in substantially straight line relation to the operating requirements of the compressor.

20 Fig. 2 is a central longitudinal section through the clearance chamber showing in greater detail one structural form which the latter may assume, and also showing in more detail a pilot control valve mechanism for the clearance chamber.

25 Fig. 3 is a detail section taken on the line 3—3 of Fig. 2, looking in the direction of the arrows.

30 Fig. 4 is a diagrammatic view showing schematically an auxiliary unloading mechanism which may be combined with the clearance chamber to obtain straight line unloading over a greater range.

35 Fig. 5 is a view similar to Fig. 1 but showing a somewhat modified and simplified form of clearance chamber.

40 The invention is illustrated in Figs. 1 and 2 as applied to a compressor cylinder 1 having a piston 2, suction passageway 3 and discharge passageway 4, the clearance chamber hereinafter described being mounted upon the cylinder head 5 of the compressor and in communication with the cylinder space at the head end of the compressor, through a passageway 6 in the cylinder head 5.

45 In the form of the invention shown in Fig. 1 a cylindrical extension 7 extends outwardly from the cylinder head 5 to surround a clearance chamber designated generally by numeral 8, and an end wall 9 fits in and is suitably clamped against the outer end of extension 7.

50 In accordance with the present invention the clearance chamber 8 is constructed to provide a portion 8a into which suitable fluid under pressure may be introduced, and from which such fluid may be withdrawn, whereby the effective volume of what may be termed the clearance

portion $8b$ of the chamber depends upon the admission or withdrawal of fluid under pressure from said chamber $8a$.

In the form of the invention under discussion a movable diaphragm 10 is interposed between the sub-chambers $8a$ and $8b$, to seal off the fluid in sub-chamber $8a$ from the gases contained within sub-chamber $8b$ and the cylinder space. The general mode of operation of the unloading mechanism as thus far briefly outlined, will first be given, with subsequent discussion of certain preferred features of construction and mode of operation of the invention in its more specific aspects.

Referring more particularly to Fig. 1, suitable fluid under high pressure, such as lubricating or other oil of similar character, may be supplied to said sub-chamber $8a$, through a pipe 11 , the flow of oil through pipe 11 into the sub-chamber being controlled by a suitable valve 12 , which may be of the pressure operated type having a diaphragm 13 . The discharge of oil from said chamber $8a$ may be controlled by a similar valve 14 having a diaphragm 15 , which is interposed in a discharge pipe 16 leading for example to the oil sump of the engine which drives the compressor. Whenever valve 12 is open permitting the introduction of more oil in sub-chamber $8a$, diaphragm 10 is moved to the right as shown in Fig. 1, thus reducing the volume of the effective clearance space $8b$ of the chamber and resulting in a decreased unloading effect upon the head end of the compressor; and conversely when valve 14 is open to permit the discharge of oil from said sub-chamber $8a$, the gaseous pressure within the compressor cylinder moves diaphragm 10 to the left, as shown in Fig. 1, thus increasing the volume of the effective clearance space of sub-chamber $8b$, and increasing the unloading effect thereof upon the compressor. Thus in the embodiment of the invention under discussion the effective clearance volume depends upon the quantity of liquid within sub-chamber $8a$, the pressure in pipe 11 being high enough to overcome the cylinder pressure when it is desired to decrease the unloading effect and the cylinder pressure ejecting liquid from sub-chamber $8a$ through pipe line 16 when it is desired to increase the unloading effect. By opening and closing the valves 12 and 14 in proper relation to the operating requirements of the compressor as existing from time to time, the volume of the effective clearance space $8b$ may be increased or decreased in straight line relation to changes in the operating requirements, so as to provide the proper clearance space for any given degree of unloading throughout the range which the clearance chamber affords.

Fig. 1 shows diagrammatically control apparatus appropriate for operating the unloading mechanism in the above manner. In Fig. 1, 17 may be understood as a control instrument of suitable type which is responsive to changes in the operating conditions or requirements of the compressor, compressors being commonly regulated according to such factors as changes in pressure in the suction, or in the discharge, or by so-called torque control. In Fig. 1 the control instrument 17 is indicated by the line 18 as being responsive to changes in pressure in the suction line leading to the compressor, and as producing corresponding changes in pressure of a pneumatic pipe 20 leading through the instrument 17 to a valve 21 of the bellows type, and having a valve plunger 22 forming a part of a

pilot valve mechanism hereinafter described in greater detail.

For the present it may be sufficient to say that this valve plunger 22 controls communication between a low pressure liquid supply line 23 which may be connected for example to the lubricating oil system of the engine which drives the compressor, and a pipe 24 which leads to the diaphragm 13 of valve 12 and also to a pipe line 25 which leads to the diaphragm 15 of valve 14 . Plunger 22 also controls communication between the pipes 24 and 25 and vent pipes 26 and 27 , which are connected to a discharge pipe 28 leading, for example, to the oil sump of the engine which drives the compressor. The sequence of operation of valve plunger 22 is such that the valves 12 and 14 are connected selectively to the pipe 23 which causes them to open, or to the pipe 28 which causes them to close, with a neutral position of plunger 22 in between, in which both valves 12 and 14 remain closed and connected to pipe 28 while the operating requirements of the compressor remain constant and in balance with the effective clearance provided by sub-chamber $8b$.

Fig. 2 shows some of the above described operating parts in greater detail, the diaphragm 10 , for example, being shown as of conical shape, so as to fit closely against the conical wall $5a$ in the cylinder head 5 , and having a central hub $10a$ fitting within passageway 6 , thus reducing to a minimum the effective clearance volume provided by sub-chamber $8b$, when the diaphragm is in the position shown in Fig. 2. The diaphragm 10 may also be provided with an annular skirt $10b$ and sealing rings $10c$, engaging with the interior wall of cylinder head extension 7 , to maintain a fluid-tight joint between sub-chambers $8a$ and $8b$.

Fig. 2 also shows the valve 21 and its plunger 22 as supported by a bracket $21a$ inside of the annular end wall 9 , the plunger 22 being received slidably within a barrel 29 having ports spaced along the plunger which are respectively in communication with the oil pressure pipe 23 , the pipe 24 leading to the admission valve 12 , the vent pipe 26 serving the admission valve 12 , the pipe 25 which is used to open the discharge valve 14 , and the vent pipe 27 serving the discharge valve.

The end portion of valve plunger 22 is shown (Fig. 2) as provided with an annular passageway $22a$ between the cylindrical collars $22b$ in such manner that in the neutral position shown in Fig. 2, the pipe 23 is in communication with neither of the pipes 24 and 25 which lead respectively to the admission and discharge valves, and the pipes 24 and 25 are in communication respectively with the vent ports 26 and 27 , so that both of the valves 12 and 14 remain closed. If the pressure in pipe 18 should increase or decrease (thus calling for increased or decreased unloading effect) plunger 22 will move in one direction or the other, thus opening communication from pipe 23 and passageway $22a$ to one of the pipes 24 and 25 , thus opening either admission valve 12 to introduce more oil into sub-chamber $8a$ while pipe 25 remains in communication with pipe 27 so that the discharge valve remains closed, thus decreasing the effective clearance volume of sub-chamber $8b$, or communication will be opened through pipe 23 of passageway $22a$ to pipe 25 , thus opening the discharge valve 14 and releasing oil from sub-chamber $8a$, so that diaphragm 10 moves to the left as shown in Fig. 2, and the effective clearance volume of sub-chamber $8b$ is increased.

ber 8b is increased, pipe 24 under these conditions remaining in communication with its vent pipe 26 so that the admission valve 12 remains closed.

Preferably the pilot valve mechanism above referred to is so arranged as to throttle the flow of oil to or from sub-chamber 8a as the chamber 8b approaches the effective clearance volume which is appropriate for the then existing operating requirements, and thereby to minimize over-regulation or hunting. For this purpose the barrel 29 of the pilot valve mechanism may be made adjustable in position according to the position assumed by the diaphragm 10, to thereby modify the action of valve plunger 22. As shown in Fig. 2 the barrel 29 is slidably supported by a cylindrical sleeve 30 surrounding it but having a longitudinal slot 31 therein through which the flexible pipes 23 and 24 to 27 above described extend, and barrel 29 is so connected to the diaphragm 10 that it moves one way or the other as the diaphragm changes its position. As shown in Figs. 2 and 3 the barrel 29 is connected to diaphragm 10 by means of a link 32 pivotally connected to the barrel and to a crank arm 33 fastened to a stub shaft 34 which penetrates through and is rotatably supported by a wall 9b which constitutes a part of end wall 9 of chamber 8a. The interior end of shaft 34 is fastened by bolt 35 to a crank arm 36 which is in turn pivotally connected to a link 37 connected at its opposite end to diaphragm 10 by means of the ball and socket members 38 and 39 which are located within hub 10a.

Thus if diaphragm 10 is moving toward the left from the position shown in Fig. 2, the plunger 22 being then in position to hold open the discharge valve 14, the link mechanism above described will move the barrel 29 to the left and thereby throttle the corresponding port openings of the pilot valve mechanism and cause them to close more quickly than would otherwise be the case, thereby preventing the diaphragm 10 from over-traveling, and bringing it gradually to rest in its proper new position. The action is similar when barrel 29 is moving to the right.

Under certain operating conditions where the diaphragm tends to remain for the most part in intermediate position without traveling to its respective limit positions, it may be desirable to force the diaphragm to travel through its full operating stroke every now and then, in order to keep clean its engaging surfaces with the extension 7, and prevent sticking of the diaphragm. For this purpose, as shown in Fig. 3, a hand-operated plunger 40 threaded into the end of valve mechanism 21 and engageable with the end of plunger 22, may be provided to supersede automatic operation through the medium of pipe 20. Under these conditions a three-way cock 41 (Fig. 1) in pipe 20 may be turned to vent the pipe, thus freeing valve mechanism 21 from its action and causing the spring 42 of the valve mechanism, which surrounds plunger 22 and engages the disk 43 fastened to plunger 22, to force the adjacent end of the plunger 22 up against plunger 40. Under these conditions adjustment of plunger 40 enables the diaphragm 10 to be manually moved throughout its entire range, in fact the automatic regulation of clearance as above described becomes superseded by manual regulation.

The degree of straight line unloading obtained by apparatus of the character above described, may be increased by combining therewith auxiliary unloading apparatus which comes into play

when the clearance chamber 8 has been adjusted to afford maximum clearance. For example, a step unloading device for the crank end of the compressor may be used in combination with a clearance chamber as above described at the head end of the cylinder, and automatic control used such that when the operating requirements call for a slightly greater degree of unloading than the clearance chamber will afford by itself, the step unloading device will be thrown into operation. The step unloading device will tend to cause unloading to a greater extent than required, and accordingly the effective clearance volume of the subchamber 8b will be reduced by control apparatus as above described, until the combined effect of the two unloading devices conforms to operating requirements. And this combined unloading effect will still vary in straight line relation to changes in the operating requirements, up to the maximum degree of unloading which the two unloading devices acting together will afford, since the clearance chamber adds to the unloading effect of the step unloading device, the additional unloading effect which is necessary to straight line regulation.

In Fig. 4 I have shown such an arrangement diagrammatically, a variable clearance chamber 44 as above described being used at the head end of the compressor cylinder, and step unloading at the crank end of the cylinder being accomplished by a diaphragm or bellows device 45 which acts to hold the compressor suction valve 46 open, to fully unload the crank end of the compressor when desired. The devices 45 and 46 will not be described in detail since suitable forms thereof are known in the art, and the variable clearance chamber 44 may be understood as automatically regulated in accordance with operating requirements, by a valve 21 having a plunger 22, etc., as above described in connection with Figs. 1 to 3.

In Fig. 4 the unloading device 45 is shown as operated by means of a pilot device having a stationary barrel 47 having a port 53 which is supplied with oil under pressure by pipe 49, and a further port 50 which supplies this oil under pressure through pipe 51 to bellows device 45 when the crank end of the compressor cylinder is to be unloaded. A pilot valve member 52 connects the ports 48 and 50 when the crank end of the cylinder is to be unloaded, and at other times vents the port 50 so that suction valve 46 of the compressor operates in the normal way.

The pilot valve 52 may be controlled by lugs 53 and 54 on plunger 22, between which is positioned an arm 55 extending out from pilot valve 52. The lugs 53 and 54 are so positioned that so long as operating requirements call for a degree of unloading which is within the range afforded by the variable clearance chamber 44, pilot valve 52 remains in a position in which the port 50 is vented, so that the unloading device at the crank end of the cylinder is not in operation. But if operating requirements call for an extent of unloading greater than the maximum afforded by the chamber 44, the plunger 22 will travel to the left (see Fig. 4) far enough to cause lug 54 to engage arm 55 and move pilot valve 52 to the position shown in Fig. 4, wherein liquid under pressure is being admitted to the diaphragm device 45 to throw the unloading device at the crank end of the compressor cylinder into operation. This will produce a marked increase in the unloading effect, and if the full additional unloading effect at the crank end of the cylinder is not

needed, plunger 22 will then move to the right (as shown in Fig. 4) far enough to regulate the effective clearance volume of chamber 44 until the combined unloading effect at the two ends of the cylinder corresponds to operating requirements. If operating requirements should then change so as to fall within the range afforded by chamber 44 acting alone, plunger 22 will move far enough to the right to cause lug 53 to engage arm 55 and thereby move pilot valve 52 to a position where port 56 is vented and the unloading device at the crank end of the cylinder cut out of operation. Thus by using a variable clearance chamber of the character above described in conjunction with other unloading devices, a straight line unloading effect is obtainable over a greater range.

In Fig. 5 I have shown schematically a somewhat modified form of unloading mechanism which is within the invention in its broader aspects. In this instance a clearance chamber 56 communicates through passageway 57 with a compressor cylinder 58, and a storage tank 59 communicates with chamber 56 through a pipe 60 having an adjustable orifice 61 therein, in such manner that liquid is interchangeable between the chambers 56 and 59. Thus the effective clearance volume of chamber 56, or the part thereof which is not occupied by liquid, depends upon the relative gaseous pressures existing in the chambers 56 and 59, and the unloading effect of chamber 56 may be increased or decreased by varying the gaseous pressure in the storage tank 59. A check valve 62 operating between valve seats 63 and 64, may be used to insure that the liquid will not pass into cylinder 58, or gas from the cylinder pass into pipe 60 when chamber 56 is adjusted to maximum clearance. As shown the valve 62 is in the form of a float operating in the perforated tube 65. Gas under pressure may be admitted to tank 59 through a valve 66 similar to the valve 12 previously described, and released from the tank by a valve 67 similar in function to the valve 14 previously described.

While the invention has been disclosed as carried out by apparatus of certain specific construction as above described, it should be understood that many changes may be made therein without departing from the invention in its broader aspects, within the scope of the appended claims.

I claim:

1. A compressor unloading mechanism including a chamber having a passageway affording communication to the cylinder space of the compressor, means for altering the effective clearance volume of said chamber to partially unload the compressor in straight line manner, a step unloading device for said compressor, and means for throwing said step unloading device into and out of operation at the limits of the unloading range afforded by said clearance chamber, thereby to afford substantially straight line unloading effect through the combined unloading range afforded by the clearance chamber and step unloading device.

2. A compressor unloading mechanism including a chamber having a passageway affording communication to the cylinder space of the com-

pressor, means for altering the effective clearance volume of said chamber to partially unload the compressor in straight line manner, an unloading device of the step type for said compressor, a control member responsive to load requirements of the compressor, said above mentioned means being responsive to operation of said control member, said unloading mechanism being also constructed and arranged to cut said step unloading device into and out of operation at the limits of the unloading range afforded by said clearance chamber and according to the load requirements of the compressor, thereby to obtain a substantially straight line unloading effect through the combined range afforded by said chamber and said step unloading device.

3. A compressor unloading mechanism including a chamber having a passageway affording communication to the cylinder space of the compressor, a movable diaphragm constituting a part of said chamber and having one face thereof exposed to the pressure obtaining in the cylinder space, a control member responsive to load requirements of the compressor, means responsive to operation of said control member for subjecting said diaphragm to fluid pressure opposing the pressure within the cylinder space, and additional means responsive to the position of said diaphragm for modifying the effect of said control member on said diaphragm.

4. A compressor unloading mechanism including a chamber having a passageway affording communication to the cylinder space of the compressor, a movable diaphragm located in said chamber and dividing the same into a clearance portion and a liquid receiving portion, means for introducing liquid under pressure into said last mentioned portion of the chamber and withdrawing said liquid therefrom to alter the position of said diaphragm and thereby alter the volume of the clearance portion of said chamber, valve mechanism for controlling the operation of said last mentioned means including a pilot valve movable in position according to load requirements of the compressor, and a valve seat member cooperating therewith, said valve seat member being movably mounted and linked to said diaphragm to modify the action of said pilot valve member.

5. A compressor unloading mechanism including a chamber having a passageway affording communication to the cylinder space of the compressor, a movable diaphragm located in said chamber and dividing said chamber into a clearance portion and a liquid receiving portion thereby to subject one face of said diaphragm to cylinder pressure and the other face of said diaphragm to the pressure of liquid in said liquid receiving portion, means for introducing liquid under pressure into said liquid receiving portion of said chamber and for withdrawing liquid from said liquid receiving portion whereby the introduction into and withdrawal of liquid from said liquid receiving portion acting in opposition to the cylinder pressure, determines the position of said diaphragm in said chamber and the effective volume of the clearance portion of said chamber.

PAUL A. CONDIT.
